NUT-ASSEMBLING MACHINE

Karl Eisele, Belleville, N. J., assignor to Camloc Fastener Corporation, New York, N. Y., a corporation of New York

Application November 18, 1943, Serial No. 510,756

15 Claims. (Cl. 10—86)

1

This invention relates to a structurally and functionally improved apparatus for the formation of nut elements and particularly elements of this nature which include a bored and threaded body to be contained within a shell and with which assembly there is associated a fiber or equivalent washer or disc.

In its more specific aspects, it is an object of the invention to furnish a mechanism of this type which will be particularly useful in constructing or assembling nut elements of the type shown, and practicing the method illustrated in the prior application for United States Letters Patent filed on June 23, 1943, in the name of J. Mills Summers, and identified under Serial Number 491,895.

It is a further object of the invention to provide a machine of this type and by means of which the several parts of the nut assembly will be disposed in proper and predetermined relationship with respect to each other and will thereupon be staked or secured in an improved manner against relative shifting.

Another object is that of designing a machine in which the completely assembled elements will be positively ejected and delivered; such delivery occurring without any liability of damage to the finished units.

An additional object is that of providing a machine which may be capable of sequentially receiving the several elements which provide a finished nut unit and grouping these elements in a predetermined and desired manner with respect to each other.

Still another object is that of furnishing an apparatus of this character which will include relatively few parts, each individually simple and rugged in construction; these parts operating with maximum speed over long periods of time and with freedom from all difficulties, to furnish units as afore described.

With these and other objects in mind, reference is had to the attached sheets of drawings illustrating practical embodiments of the invention, and in which:

Fig. 1 is a fragmentary plan view of the dial plate or turntable of the apparatus;

Fig. 2 is a longitudinal sectional view taken along the lines 2—2 and in the direction of the arrows as indicated in Fig. 1;

Figs. 3 and 4 are fragmentary transverse sectional views taken respectively along the lines 3—3 and 4—4 and in the direction of the arrows as also indicated in Fig. 1;

Fig. 5 shows in elevation and plan the several parts of the nut assembly which are to be staked by the present apparatus;

Fig. 6 is a sectional plan view taken along the lines 6—6 and in the direction of the arrows as indicated in Fig. 2;

Fig. 7 is a fragmentary sectional view taken through a portion of a dial mechanism forming a part of a machine which is intended to sequentially receive the successive parts of the nut assembly;

Fig. 8 is a view similar to Fig. 7 and showing the washer element in position within the shell of the nut unit;

Fig. 9 illustrates the body of the nut in position upon the fiber washer; and

Fig. 10 is again a transverse sectional view of the parts as shown in Figs. 7 to 9 inclusive, but additionally illustrating the mechanism whereby a predetermined and desired relationship of these parts is established.

With primary reference to Fig. 5, it will be seen that the reference numeral 15 indicates a shell which is formed with a centrally depressed well portion 16, the base of which is apertured as indicated at 17. The body may be extended as at 18 to provide what might be termed wing portions. These are conveniently apertured to receive rivets or other fastening elements for securing the shell with respect to a mounting surface.

As will be noted, the well portion 16 is preferably of non-circular configuration. A washer 19 of similar configuration is provided. This washer is preferably formed of fiber or similar material. The washer or disc is centrally apertured as at 20; the inner face of this bore being unthreaded.

Still with reference to Fig. 5, a nut 21 is also provided. This nut has its bore threaded as at 22. It also has an external configuration preferably corresponding to the inner configuration of the well portion 16. The edges of the nut are formed with grooves 23, the base portions of which may be arcuate or substantially straight as desired.

As disclosed in the prior Summers application, the disc or washer 19 is disposed within the shell 15 and adjacent the base of the well portion. In turn, disposed to overlie the washer is the nut 21. The purpose of the present apparatus is that of establishing a proper position and relationship of these several parts and in staking the assembly so that subsequent movements of one part with respect to the other is prevented. This will result

in the production of a unit which is compact and

ready for use. At will be hereinafter apparent, the parts may be automatically assembled in the machine or else assembled prior to association therewith; a machine constructed in accordance with the present invention serving to properly dispose the parts of the assembly and secure them against movement. In the interest of simplicity of design, it is in certain respects preferred to group the parts of the nut assemblies prior to their association in the machine.

Thus referring to Fig. 1, it will be seen that the numeral 24 indicates a dial. This is rotatably supported as, for example, at 25 above a bed plate 26 as shown in Fig. 2. The dial 24 is intermittently rotated or indexed around its center point. This may be achieved by any desired type of drive. Likewise, by means of a suitable drive, a head 27 as especially shown in Figs. 2 and 3 is caused to reciprocate. The projection of this head is timed to occur during the interval of 20 rest of the dial. It is only when the former is retracted to a position removed from cooperation with the units associated with the dial, that the latter is indexed or advanced.

Now with reference to the detailed structure of the head 27 it will be seen as especially shown in Figs. 2 and 3 that the latter includes a body mounting an actuating wedge 28. This body also mounts a plunger 29 which may be identified as a tamping member. The latter is provided with a contacting portion 30 having a configuration corresponding to the configuration of the upper face of the shell 15. A spring-pressed pin 31 of an area in excess of that of the bore 22 of the nut 21 is carried by the plunger 29. In line with the 35 wedge element 28 and at the station beyond that at which plunger 29 operates, the head supports a spring-pressed plunger 32. The latter has a contact or foot portion 33 substantially corresponding to the portion 30 of plunger 29. Plunger 32, when unrestrained, is normally projected to a position materially beyond the foot portion 30 of plunger 29. In retracted position it extends in the same plane as foot portion 30. As will be seen with particular reference to Fig. 1, the dial 40 plate of assembly actually comprises a series of similar units positioned one beside the other. The dial indexing or rotating mechanism advances the dial in each step through a distance equal to the width of the units. The head has 45 pure reciprocatory movements.

The mechanism present in each of the units providing the dial assembly has been particularly shown in Fig. 6. As will be seen in that view, a pair of opposed staking jaws or punches 34 are slidably mounted in block 36. The latter provide in aggregate a recess 37 to receive the well portion 16 of the shell. The jaws or punches 34 are preferably spring retracted. To this end, a spring bow 38 may be employed which is secured to the assembly by, for example, a clamp 39. The arms of the bow 38 extend into recesses forming a part of the jaws.

Operating levers 40 are pivotally supported as at 41 and have their arms disposed in contact with and extending beyond the outer ends of the jaws or punches 34. The opposite arms of the levers normally extend in line with an opening 42 formed in the base plate 43 of the assembly. The spring 38 normally swings these levers to such a position. The block 36 acts as a stop to limit the inward movements of these levers. The opening 42 in the plate 43 is so disposed that it will accommodate the wedge 28. Accordingly, as the latter is projected, the adjacent ends of the 75

levers will be contacted thereby and separated. This will force the opposite ends of the levers inwardly. Such action will have the result of projecting the jaws or punches 34.

As will be appreciated, the jaws of these punch portions will be curved if an arcuate indentation is to be formed in the shell 15 (and if the groove 23 of the nut is arcuate in shape). If that groove is of another configuration, then the jaw portion of the punches will be correspondingly modified.

A plate 44 is disposed to overlie this entire assembly. The plate has an opening of a configuration corresponding to the outline of the shell 15. This opening is aligned with respect to the recess provided by the block 36 in conjunction with the jaws 34. The plate is moreover formed with an opening 45 in line with the opening 42. Therefore, the wedge 28 may be brought to a position between the adjacent ends of the operating levers. Also, the upper plate permits the shell to be supported upon the block 36 while framed by the opening in its body.

As will be understood, the nut assemblies including the fiber washers and nuts are disposed 25 one within each of the plate openings and well in advance of the head 27. As they reach positions adjacent the latter, the tamping plunger 29 will descend. Accordingly, the spring-pressed pin 31 will engage the adjacent surface of the 30 nut 21 and force the latter against the washer. The washer will in turn be somewhat compressed and forced against the base of the shell. An assurance of the proper disposition of the several parts will be had in that the foot portion 30 of the 35 plunger moves to a position actually below the surface of the upper plate 44 and within the opening defining the shell.

Upon the ascent or retraction of the head 27 the dial is indexed to the next station. At that station and with the projection of the head, the foot portion 33 of the plunger 32 engages and bears with increasing pressure against the face of the assembly. At the moment when this pressure is adequate to assure against any possibility of displacement, the wedge 28 engages the levers and causes the latter to be swung so that the staking punches 34 are projected. In such projection the material of the shell will be forced into the grooves 23 of the nuts. Accordingly, all parts of the latter assembly will be locked against displacement.

Now with a view to providing a mechanism which will deliver the assembly from the dial plate, it will be observed as especially shown in Fig. 2 that plungers 46 are slidably carried, one by each of the units of the dial. The upper surfaces of these plungers have an area in excess of the bore of the shell or disc 19. Secured to the bed plate 26 of the machine is a cam member 47. The latter is disposed in the path of movement of the lower ends of the plungers 46, and they are of a length such that when engaging the cam they will project above the face of the dial. Accordingly, and as shown especially in Fig. 2, the 60 plungers will expell the shell assemblies from the well portions of the dial and after the staking operation has been completed.

The assemblies will be maintained in this expelled position until—as the dial continues to intermittently rotate—they move to positions adjacent a tangentially extending guide 48. In turn disposed in line with the latter a chute 49 may be provided. It is obvious that as the dial rotates, and with the nut assemblies elevated, the latter will be displaced sideways over the dial

and finally delivered through the chute 49 or its equivalent. Thereafter, the plungers 46 move beyond the cam 47, whereupon they assume their fully retracted positions. Under certain conditions, it might be desired instead of assembling the parts of the nut unit prior to their association with this machine, they might be assembled within the machine and prior to the operations just described.

If such a result is to obtain, it is apparent that as shown in Fig. 7 the shell might be delivered in any desired manner to the upper face of the dial plate and so that the well portion 16 of the former would be disposed in one of the corresponding portions of the latter. Thereupon, as shown in Fig. 8 a washer element 19 could be disposed within the shell. Subsequently and as illustrated in Fig. 9, a nut 21 could be positioned within the shell and upon the washer or disc 19. Following such a disposal of the parts, the tamping plunger 29 would operate in the manner heretofore described to assure a disposition of the washer and nut not alone proper with respect to each other but also with respect to the shell. Beyond this station the staking operation would occur.

From the foregoing, it will be appreciated that a mechanism is provided which, among others, will accomplish the objects specifically set forth in the preamble to this specification. It is also obvious that numerous changes in construction and rearrangements of the parts might be resorted to without departing from the spirit of the invention as defined by the claims.

I claim:

1. In an apparatus of the character described, a dial presenting recesses to receive shells which are in turn to receive nut elements formed with grooves in their side walls, and staking means slidably supported with respect to said dial and adjacent said recesses to cause the material of said shells to be projected into the grooves of said nuts.

2. In an apparatus of the character described, a dial presenting recesses to receive shells which are in turn to receive nut elements, and staking means slidably supported with respect to said dial and adjacent said recesses to cause the material of said shells to be projected into locking contact with said nut elements, and means for maintaining said elements in proper positions with respect to said shells.

3. An apparatus of the character described including in combination a dial formed with recesses to receive shells and means for deforming portions of said shells, a head cooperative with said dial, a tamping member mounted by said head, and a clamping element also mounted by said head.

4. An apparatus of the character described including in combination a dial formed with recesses to receive shells and means for deforming portions of said shells, a head cooperative with said dial, a tamping member mounted by said head, a clamping element also mounted by said head, and a spring for normally projecting said clamping element.

5. An apparatus of the character described including in combination a dial formed with recesses to receive shells and means for deforming portions of said shells, a head cooperative with said dial, a tamping member mounted by said head, a clamping element also mounted by said head, and a spring-pressed plunger mounted by

said tamping member and normally projecting said plunger in the direction of said dial.

6. An apparatus of the character described including in combination a dial formed with recesses to receive shells and means for deforming portions of said shells, a head cooperative with said dial, a tamping member mounted by said head, a clamping element also mounted by said head, and means also carried by said head for operating the deforming means of said dial.

7. An apparatus of the character described including in combination a dial formed with recesses to receive shells, means for deforming portions of said shells, and shell-projecting means, a head cooperative with said dial, a tamping member mounted by said head, and a clamping element also mounted by said head.

8. A staking assembly including a block formed with a shell-receiving recess and with guiding grooves extending toward said recess, staking jaws slidably mounted within said grooves, and means for projecting said jaws.

9. A staking assembly including a block formed with a shell-receiving recess and with guiding grooves extending toward said recess, staking jaws slidably mounted within said grooves, means for projecting said jaws, and resilient means for retracting said jaws.

10. A staking assembly including a body, arms pivotally mounted by said body, jaws slidably supported by said body and cooperable with said arms to be projected as the latter are rocked, and said body being formed with an opening to receive a wedge-shaped element between said arms to rotate the latter.

11. An apparatus of the class described including, in combination, a dial plate formed with a recess to receive a shell, staking means carried by said dial and cooperable with said shell, means for rotatably supporting said dial, and a shell-expelling plunger mounted by said dial and underlying said shell.

12. An apparatus of the class described including, in combination, a dial plate formed with a recess to receive a shell, staking means carried by said dial and cooperable with said shell, means for rotatably supporting said dial, a shell-expelling plunger mounted by said dial and underlying said shell, and cam means cooperative with said plunger for operating the latter as said dial rotates.

13. An apparatus of the class described including, in combination, a dial plate formed with a recess to receive a shell, staking means carried by said dial and cooperable with said shell, means for rotatably supporting said dial, said shell and dial being adapted to receive a washer upon subsequent rotation of said dial, and said shell and washer being adapted to receive and support a nut upon a still further rotation of said dial occurring.

14. An apparatus of the class described including, in combination, a dial plate formed with a recess to receive a shell, staking means carried by said dial and cooperable with said shell, means for rotatably supporting said dial, said shell and dial being adapted to receive a washer upon subsequent rotation of said dial, said shell and washer being adapted to receive and support a nut upon a still further rotation of said dial occurring, means forming a part of said apparatus for tamping said nut and washer into predetermined positions with respect to each other and with said shell, and means for thereupon staking

said shell into locking engagement with said nut.

15. An apparatus of the class described including, in combination, a dial plate formed with a recess to receive a shell, staking means carried by said dial and cooperable with said shell, means for rotatably supporting said dial, said shell and dial being adapted to receive a washer upon subsequent rotation of said dial, said shell and washer being adapted to receive and support a nut upon a still further rotation of said dial occurring, means forming a part of said apparatus for tamping said nut and washer into predetermined positions with respect to each other and with said shell, means for thereupon staking said shell 15 into locking engagement with said nut, means

for maintaining the established positions of said shell, nut and washer during the staking thereof, and means for thereupon expelling said shell, nut and washer from said dial recess.
